UNITED STATES PATENT OFFICE.

STEPHEN E. MCPARTLIN, OF CHICAGO, ILLINOIS.

LATCH MECHANISM.

Application filed February 4, 1925, Serial No. 6,742. Renewed April 4, 1927.

My invention relates more particularly to latch mechanism for swinging doors which are either relatively heavy, as in the case of doors of cold storage buildings, or otherwise present considerable resistance to opening.

One of the primary objects of my invention is to provide a construction of latch mechanism whereby the door may be unlatched and moved to open position by a single act of the operator, and preferably unlatched and opened by either a straight pull by the operator located at the outer surface of the door, or by a straight push exerted by the operator at the inner surface of the door, to the end that a separate handle for opening the door, after it is unlatched, may be obviated. Another object is to provide for the automatic latching of the door in the swinging of the latter to closed position; another object is to provide a construction of latch device, particularly having the characteristics above stated, which may be applied to operative position on either a right-hand or left-hand door; another object is to avoid shock or undue jar to the hand of the operator in closing the door.

Referring to the accompanying drawings: Figure 1 is a view in front elevation of a portion of a door-equipped wall, showing my improved latch mechanism applied thereto. Figure 2 is a plan sectional view of the structure shown in Fig. 1, the structure in these two views being shown in latched position; and Figure 3, a fragmentary, plan sectional view of a portion of the structure shown in the preceding figures, this view showing the latch mechanism in released position.

The particular illustrated construction involves a supporting plate 5 adapted to be applied to the face of a door and secured thereto as by means of the screws represented at 6, this plate being provided at one end with a boss 7 apertured as indicated at 8, and at its opposite end with a strap member 9 secured to the plate 5 as by screws 10 and forming between its ends a guide portion 11 for the latch bar hereinafter described, the plate 5 between its ends being provided with spaced-apart lugs 12 extending lengthwise of the plate.

The latch bar referred to is represented at 13, this bar being slidable in the guide portions 8 and 11 and carrying at its outer, yoke-shaped, end 14, a roller 15 journaled therein

as represented at 16. The bar 13 between the boss 7 and the strap 9, is provided with a head 17 between which and the boss 7, a coiled spring 18 surrounding the bar 13, is confined, this spring yieldingly forcing the bar 13 to the right in Figs. 1 and 2.

Extending between the lugs 12, and pivotally supported thereon at a vertically-disposed pivot 19, is a lever 20, one end of which, represented at 21, opposes an inclined cam-face 22 on the head 17, the other end of this lever, and represented at 23, being provided with a removable handle portion 24 shown as extending upwardly and at an angle to the lever 20, this handle portion being spaced a sufficient distance from the adjacent portions of the latch mechanism, to permit the operator to readily grasp it without obstruction. The arrangement of the parts described is such, as shown, that when the lever 20 is rotated in counter-clockwise direction as in Fig. 2, as for example to the position shown in Fig. 3, the latch bar 13 will be shifted to the left against the action of the spring 18 for disengaging it from the keeper hereinafter referred to.

The mechanism shown also comprises a push rod 25 which is pivotally connected at 26, to the arm 23 of the lever 20 and extends rearwardly therefrom through an opening 27 in the plate 5 to afford means whereby the lever 20 may be rocked, for shifting the latch rod 13 against the action of the spring 18, by a pushing action instead of by a pulling action as in the case of the use of the hand grip 24.

The mechanism also involves a keeper represented at 28 adapted to be applied to a plate portion 29 to the front surface of the wall surrounding the door opening, as by bolts represented at 30, the keeper 28 containing a recess 31 adapted to co-operate with the roller 15, and being beveled beyond this recess, as indicated at 32.

In the arrangement shown, a portion of the wall surrounding the door opening of a cold storage room, is represented at 33, the door-opening at 34 and the door controlling the opening at 35. The plate member 5 with the parts carried thereby is shown as secured to the outer face of the door 35 and the push rod 25 is shown as slidably extending through aligning openings 36 in the door 35, whereby the expanded inner portion 37 of the push rod is exposed for operation, at the inner surface of

the door. The keeper 28 is secured to the outer surface of the wall 33 in such position that the latch-bar 13, in the normal position of the latching mechanism extends into the recess 31 and maintains the door 35 in closed position.

To release the latch-bar 13 from the keeper 28 and open the door 35 from the outside, the operator grasps the handle portion 24 and pulls outwardly thereon thereby 10 rocking the lever 20 and moving the latch-bar 13 to the left in the drawings against the resistance of the spring 18 to a position in which this bar is disengaged from the keeper 28, and by continuing the pull on the lever pulls the door open. To unlatch and 15 open the door from the inner side of the door, the operator merely pushes on the push rod 25 which operates first to disengage the latch-bar from the keeper and thereafter, by continuing the pushing force, to push the door open.

It will thus be understood from the foregoing that the door is unlatched and opened, 25 by a single operation performed by the operator, namely, a pull when the operator is at the outer surface of the door and a push when the operator is at the inner surface of the door.

30 The arrangement of the keeper relative to the other portions of the latching mechanism, is such, as shown, that the latch-bar 13 automatically interlocks with the keeper 28 at its recess 21, upon the mere act of pushing the door closed, the beveled surface 32 operating to cam the latch rod 13 to the left in the drawings until the latter registers with the recess 31 whereupon the spring 18 forces the latch-bar to a position in which 35 it is interlocked with the keeper as shown in Fig. 2.

40 It will furthermore be noted that the latching mechanism shown in the form illus-

trated and by reason of the provision of the vertical pivot for the lever 20 is adapted to be applied to operative position on either a right-hand or a left-hand door, the handle-portion 24 being positioned on the lever to extend upwardly, which is of considerable advantage inasmuch as it avoids 45 the necessity of providing separate right and left constructions. Furthermore, a structure of the form described is not only durable and positive in operation, but by its use heavy doors may be rigidly manipulated 50 and moved to closed position without shock to the hand of the operator.

While I have illustrated and described a particular construction involving my invention I do not wish to be understood as 60 intending to limit it thereto, as the same may be variously modified and altered without departing from the spirit of my invention.

What I claim as new, and desire to secure 65 by Letters Patent, is:

Latch mechanism comprising a support, a latch-bar movable on said support, a keeper for engagement by said latch-bar, a spring urging said latch bar into engagement with 70 said keeper, a lever pivotally supported between its ends on a vertical axis, said latch-bar presenting a surface facing toward said keeper for engagement with one end of said lever, said lever when operated actuating 75 said latch-bar against the resistance of said spring and out of engagement with said keeper, the other end of said lever being adapted to be grasped by the operator for actuating it, said latch-bar being adapted to 80 move in opposition to its spring when riding against said keeper without actuating said lever, and a push rod movable crosswise of the path of movement of said latch-bar and engaging said lever for actuating the latter.

STEPHEN E. McPARTLIN.
